UNITED STATES PATENT OFFICE.

CHRISTIAN L. HANSON, OF MINNEAPOLIS, MINNESOTA.

PHOTOGRAPHIC-PRINTING MACHINE.

1,090,915.

Specification of Letters Patent. Patented Mar. 24, 1914.

Application filed August 4, 1913. Serial No. 782,806.

To all whom it may concern:

Be it known that I, CHRISTIAN L. HANSON, a citizen of the United States, residing at Minneapolis, in the county of Hennepin and State of Minnesota, have invented certain new and useful Improvements in Photographic-Printing Machines; and I do hereby declare the following to be a full, clear, and exact description of the invention, such as will enable others skilled in the art to which it appertains to make and use the same.

My invention has for its object to provide a simple and highly efficient photographic printing machine, adapted for duplication of prints from a negative.

Generally stated, the invention consists of the novel devices and combinations of devices hereinafter described and defined in the claims.

In the accompanying drawings which illustrate the invention, like characters indicate like parts throughout the several views.

Referring to the drawings, Figure 1 shows the improved printing machine in front elevation, some portions being broken away; Fig. 2 is a fragmentary view in front elevation showing certain parts found at the upper right-hand portion of Fig. 1; Fig. 3 is a view corresponding to Fig. 1 but illustrating different positions of certain of the parts; Fig. 4 is an oblique section taken on the line $x^4 x^4$ of Fig. 3; Fig. 5 is a vertical section taken on the line $x^5 x^5$ of Fig. 3; Fig. 6 is an oblique section taken on the line $x^6 x^6$ of Fig. 1; Figs. 7 and 8 are oblique sections taken on the line $x^7 x^8$ of Fig. 1, some parts being broken away; Figs. 9 and 10 are oblique plan views with some parts shown in diagram, showing particularly a feed escapement found in the vicinity of the line marked $x^9 x^{10}$ on Fig. 1; Fig. 11 is a detail in section on line $x^{11} x^{11}$ of Fig. 8; and Fig. 12 is a section on line $x^{12} x^{12}$ of Fig. 1.

In this improved photographic printing machine, the printing frame, the negative holder, and various associated parts are set obliquely in a vertical plane, for certain important reasons which will hereinafter appear. The said printing frame 1 is a rectangular structure which, as shown, is directly secured to an upright plate 2 which, in turn, is supported by a pedestal-like framework 3. The plate 2 has a rectangu-

lar opening that alines with the rectangular opening in the printing frame 1 (see particularly Fig. 5).

The negative 4, which, as shown, is formed in a glass plate, is directly held in the usual or in any suitable way, by a rectangular negative holder or frame 5. The numeral 6 indicates a mask of paper or other suitable material, shown as applied on the outer face of the negative and held to the negative holder 5 by any suitable means, as, for instance, by spring fingers 7 applied to the said negative holder.

The numeral 8 indicates a card guiding rail which is alined with the oblique lower portion of the printing frame 1 and is rigidly secured thereto but spaced apart therefrom, at its end, so that the negative holder 5 and the lower edge of the mask 6 may be inserted between the said parts 1 and 8, as best shown in Figs. 7 and 8, but also indicated by dotted lines in Fig. 3 (see also Figs. 5 and 6). The upper and lower end portions of the negative holder 5 are also arranged to be slipped under the inwardly projecting end of the retaining bars 9 secured on the upper rail of the frame 1. Furthermore, the upper end portion of the negative holder is adapted to be slid under the lower edge of a feed board 10, which latter is obliquely set in a vertical plane and is rigidly secured to the printing frame 1 and to the card guiding rail 8 (see Figs. 9 and 10).

As a simple and efficient means for frictionally clamping the oblique lower portion of the negative holder 5 against the bar 8, I insert a clamping bar 11 into a suitable seat formed therefor in the printing frame 1 (see particularly Fig. 4 but also note dotted lines Fig. 3). At its ends, the clamping bar 11 is reduced and formed with cam surfaces that engage with small cam blocks 12 on the frame 1 and are subject to retaining springs 13 attached at their outer ends to the frame 1.

The numeral 14 indicates a small lever (see Fig. 3) pivoted to the frame 1 and having its upper end engaged with a notch in the clamping bar 11. By movements of the lever 14 the clamping bar 11 may be moved endwise, and, under action of the cam blocks 12, caused to clamp or release the negative holder at will.

For pressing the sensitized paper or card against the negative, I provide a platen or

presser board 15, the lower edge of which is set against the inclined upper edge of the guide bar 8, so that the said platen is set obliquely in a vertical plane and is alined with the negative holder and the rectangular opening in the frame 1. This platen 15 is carried by a plunger 16 mounted for sliding movements through a supporting bar 17. There should be a yielding movement between the platen and plunger to insure even pressure on the negative, and for certain other reasons, and this is conveniently accomplished by providing the inner end of the plunger 16 with a plate-like head 18, that is loosely connected to the platen by screws 19, and interposing bowed springs 20 between the said platen and head (see particularly Figs. 1 and 6).

At its upper end, the supporting bar 17 is pivotally connected to a stud 21 secured on the upper portion of the frame 1. At its free lower end, said bar 17 is normally seated in the notch of a stop lug 22 secured on the lower portion of bar 8. The lower end of said bar 17 is thus held in working position against outward lateral movement, but may at any time be lifted off of the lug 22, carrying the platen with it. Fig. 3 shows the bar 17 and platen turned into an extreme upper and inoperative position with the said bar resting against a stop 23 on the upper portion of the frame 1.

For moving the platen toward and from the negative, a lever 24 is intermediately pivoted to a lug 25 on the bar 17 and, at its inner end, has a sliding pivotal connection to the plunger 16. The other end of said lever 24 normally engages between the pronged end of a lever 26 that is pivoted to a bearing 27 on the lower end of the guide bar 8. Preferably, the lever 24 has a laterally offset roller for direct engagement with the pronged end of the lever 26. The other end of the lever 26 is pivotally connected to the lower end by a long oblique link 28, the upper end of which is pivoted at 29 to a crank head 30 which, in turn, is journaled to bearings 31, shown secured to and depending from the upper end portion of the bar 8. The crank head 30 is provided with an operating handle 32.

It should have been noted that the platen 15 is provided with a laterally projecting guide pin 33 (see Figs. 1 and 6), which works through a perforation in the supporting bar 17 and holds the said platen against rotation.

Secured to the board 2, in a position to receive the printed cards or prints which are directed thereto by the guide bar 8, is a catch box 34. In Fig. 1, the character *y* indicates the printed card.

The cards to be printed are placed one at a time on the upper end of the guide bar 8 and against the upright feed board 10

and with the lower edge thereof engaging with and stopped by a so-called feed escapement dog 35. This dog 35, as shown, is pivoted on a stud 36 and a bracket 37 secured on the bar 8, and is provided with a weighted arm 38 which yieldingly holds the free end of said dog against the feed board 10. The numeral 39 indicates a dog releasing lever (see Figs. 9 and 10), which is intermediately pivoted to the noted bracket 37. One end of this lever 39 is engageable with a projection 35^a of the feed dog 35, and the other end thereof is arranged to be engaged by the platen when the latter is moved outward.

At the lower end of the platen is a so-called discharge escapement having a novel and peculiar action and, as preferably constructed, involving the following details, which details are best shown in Figs. 1, 7 and 8:—Of these parts, the numeral 40 indicates an escapement arm pivotally attached to the lower end of the platen 15, at its upper end, and provided, at its free end, with a segmental portion 41 formed with ratchet teeth 42 on its inner edge. Said arm 40 also preferably has an applied weight 43. To the end of the segmental portion 41 of the said arm is attached an escapement head 44, preferably of some light material, such as wood, which will normally be gravity held against the negative or its mask, so that it will prevent a card *y*, which has been slid by gravity on the guide bar 8 between the platen and negative, from passing on downward and into the catch box. Hence, this head 44 affords a stop for intercepting the card and stopping the same in position for printing.

The numeral 45 indicates a gravity operated latch which is pivoted to a supporting bracket 46 on the lower end of the platen, and normally engages the ratchet teeth 42. This latch 45, when the platen is moved toward the negative, will slip over the teeth 42, and, when the platen is retracted or moved away from the negative, will cause the arm 40 and head 44 to move with the platen and thereby release the printed card and permit the same to slide, under action of gravity, downward on the bar 8 and into the catch box 34.

For releasing the latch 45, after the printed card has been permitted to drop, and thereby permitting the arm 40 to move the escapement head 44 back against the negative or mask before the next card has been released by the feed dog or escapement 35, I provide the crooked tripping lever 47 which is intermediately pivoted to the bracket 46, with its upper end immediately underlying the said latch and with its other end in position to be forced against the supporting bar 17, when the platen nearly reaches the outermost position away from

the negative, and at a time just before the platen strikes the tripping lever 39, to release the feed dog 35.

The upper surface of the guide bar 8 is preferably made slightly concave in cross section, so that the cards, in passing over the same, will be carried away from the negative and, hence, move under less friction. Also, this channel form of the bar insures more accurate alinement of the card with the negative, when it is pressed by the platen toward and against the negative.

A light for printing may be furnished by different sources. In some instances it may be daylight. Where artificial light is employed, it may be from an electric lamp or from an oil burning lamp, and it is this latter arrangement that is illustrated in the drawings. As shown in Fig. 5, the numeral 20 48 indicates a lamp chamber in which is the suitable lamp 49. In this lamp chamber, between the lamp and the board 2, to which the said lamp chamber is applied, is a sheet metal partition 50 having a light passage 25 that is adapted to be opened and closed by a shutter 51 (see also Fig. 3), which shutter is carried by the end of an arm 52 secured to a short rock shaft 53 (see Fig. 3). The forwardly projecting front end of the shaft 30 53 has a short arm 54 connected by a slot and pin coupling 55 to the lower end of a link 56, the upper end of which is pivoted at 57 to the crank head 30 already described.

The actions of the various parts have already been described, but the relative timing thereof may be briefly summed up in the following statement:—Under downward movement of the operating handle 32, the shutter 51 will remain in a closed position while the platen is being moved to press the card against the negative; and a subsequent downward movement of the said handle, to wit, from the broken line position to the dotted line position (Fig. 1), will move the shutter into open position, and will compress the platen springs 20. When the handle 32 is in the lowermost position, shown by full lines in Fig. 2, and by dotted lines in Fig. 1, the pivot 29 of the link 28 is thrown 50 below a dead center, so that the platen will then be locked in a position to hold the card or print against the negative. Under upward movement of the operating handle 32, from its dotted line to its broken line position (Fig. 1), the shutter 51 will be closed, and further upward movement of the said handle will cause the platen to be retracted and the printed card to be released. The feed dog or escapement 35 is retracted while 60 the handle 32 is being moved upward from its broken line to its dotted line position (Fig. 2); and, as already stated, the discharge escapement is released by the platen just in advance of the release of the said feed escapement.

What I claim is:—

1. The combination with a negative holder and a co-operating platen, of an oblique guide bar for directing cards between said platen and negative holder, a platen operating device, and feed and discharge escapements operated with a properly timed action by said platen operating device, to control the delivery of cards between said platen and negative holder. 75

2. The combination with a printing frame having an oblique card guide bar, of a negative holder applied to said printing frame adjacent to said guide bar, a platen supporting bar movable to and from an operative position, a platen supported by said bar, and platen operating connections. 80

3. The combination with a printing frame having an oblique card guide bar, of a negative holder applied to said printing frame adjacent to said guide bar, a platen supporting bar movable to and from an operative position, a platen supported by said bar, and platen operating connections, including a crank head having an operating handle, and a link connected to said crank head and movable from one side to another from a dead center and serving, in one position to hold the said platen pressed toward said negative holder. 85

4. The combination with a printing frame having an oblique card guide bar, of a negative holder applied to said printing frame adjacent to said guide bar, a platen supporting bar movable to and from an operative 100 position, a platen supported by said bar, and platen operating connections, including parts that are moved into and out of operative connection by movements of said platen supporting bar. 105

5. The combination with a printing frame having an oblique card guide bar, of a negative holder applied to said printing frame adjacent to said guide bar, a platen supporting bar movable to and from an operative position, a platen supported by said bar, and platen operating connections, the said platen operating connections including parts that are moved into and out of operative connection by movements of said 110 platen supporting bar. 115

6. The combination with a printing frame having an oblique card guide bar, of a negative holder applied to said printing frame adjacent to said guide bar, a platen supporting bar movable to and from an operative position, a platen supported by said bar, platen operating connections, and a light controlling shutter operated with a properly timed action by said platen operating 120 connections. 125

7. The combination with a negative holder and a support therefor, of a platen supporting bar pivoted at its upper end and normally held in an operative position 130

- against a fixed stop, a platen mounted on said platen supporting bar and movable toward and from said negative holder, and platen operating connections.
- 5 8. The combination with a negative holder and a support therefor, of a platen supporting bar pivoted at its upper end and normally held in an operative position against a fixed stop, a platen mounted on said platen supporting bar and movable toward and from said negative holder, and platen operating connections, including a yielding spring element.
- 13 9. The combination with a negative holder and a support therefor, of a platen supporting bar pivoted at its upper end and normally held in an operative position against a fixed stop, a platen mounted on said platen supporting bar and movable toward and from said negative holder, platen operating connections, and feed and discharge escapements controlling the delivery of cards between said platen and negative holder and arranged to be operated by the said platen operating connections with properly timed actions.
- 20 10. The combination with a negative holder and a support therefor, of a platen supporting bar pivoted at its upper end and normally held in an operative position against a fixed stop, a platen mounted on said platen supporting bar and movable toward and from said negative holder, platen operating connections, including a yielding spring element, and feed and discharge escapements controlling the delivery of cards between said platen and negative holder and arranged to be operated by the said platen operating connections with properly timed actions.
- 25 11. The combination with a negative holder and a support therefor, of a platen supporting bar pivoted at its upper end and normally held in an operative position against a fixed stop, a platen mounted on said platen supporting bar and movable toward and from said negative holder, platen operating connections, including a yielding spring element, and a light controlling shutter arranged to be operated by said platen operating connections, during a time when the yielding elements thereof is under compression and the platen is held against said negative holder.
- 30 12. The combination with a negative holder and a support therefor, of means for guiding cards between said platen and negative holder, a platen supporting bar pivoted to said support at its upper end and normally held against the fixed stop on said support, a lever intermediately pivoted to said platen supporting bar and connected at one end to said platen, an intermediate lever on the said support detachably engageable with the other end of the lever on said platen supporting bar, a link connected to said intermediate lever at one end, a crank head connected to the other end of said link and having an operating handle, and a light controlling shutter having an operating connection controlled by said crank head to move said shutter with a properly timed action in respect to said platen.
- 35 13. The combination with a negative holder and a support therefor, of means for guiding cards between said platen and negative holder; a platen supporting bar pivoted to said support at its upper end and normally held against the fixed stop on said support, a lever intermediately pivoted to said platen supporting bar and connected at one end to said platen, an intermediate lever on the said support detachably engageable with the other end of the lever on said platen supporting bar, a link connected to said intermediate lever at one end, a crank head connected to the other end of said link and having an operating handle, and a light controlling shutter having an operating connection controlled by said crank head to move said shutter with a properly timed action in respect to said platen.
- 40 14. The combination with a negative holder and a support therefor, of means for guiding cards between said platen and negative holder, a platen supporting bar pivoted to said support at its upper end and normally held against the fixed stop on said support, a lever intermediately pivoted to said platen supporting bar and connected at one end to said platen, an intermediate lever on the said support detachably engageable with the other end of the lever on said platen supporting bar, a link connected to said intermediate lever at one end, a crank head connected to the other end of said link and having an operating handle, and feed and discharge escapements actuated by movements of said platen.
- 45 15. The combination with a negative holder and a support therefor, of a platen movable toward and from the said negative holder, platen operating connections, a discharge escapement for controlling the discharge of printed cards from between the said platen and negative holder, said escapement comprising a lever pivoted to said platen and provided with a segmental free end portion having ratchet teeth, a stop head, a retaining dog operated on the said ratchet teeth to retract the said lever when the platen is retracted, and means for releasing said retaining dog, approximately at the limit of the movement of said platen away from said negative holder, and thereby, at such time, releasing said escapement lever and permitting the same to again become operative.
- 50 16. The combination with a printing frame and a card guiding bar secured in respect thereto, the said bar being spaced from said frame to permit a negative holder to be inserted between the same, of a clamp-

ing bar applied to said printing frame and alined with said guide bar and operated to clamp said negative holder against said bar, substantially as described.

5 17. The combination with a negative holder and a coöperating platen, of an oblique guide bar for directing cards between said platen and negative holder, a platen operating device, and feed and dis-
10 charge escapements operated with a properly timed action by said platen operating device,

to control the delivery of cards between said platen and negative holder, and a catch box having an open side located at the lower end of said oblique guide bar for receiving the 15 printed cards.

In testimony whereof I affix my signature in presence of two witnesses.

CHRISTIAN L. HANSON.
